UNITED STATES PATENT OFFICE

147,878

DESIGN FOR A HANDLE FOR HAND
LUGGAGE

Clifford Brooks Stevens, Milwaukee, Wis., assignor to Wheary Incorporated, Racine, Wis., a corporation of Wisconsin

Application December 13, 1946, Serial No. 135,475

Term of patent 14 years

(Cl. D87—2)

To all whom it may concern:

Be it known that I, Clifford Brooks Stevens, a citizen of the United States, residing at Milwaukee, in the county of Milwaukee and State of Wisconsin, have invented a new, original, and ornamental Design for a Handle for Hand Luggage, of which the following is a specification, reference being had to the accompanying drawings, forming part thereof.

This application is a continuation in part of the co-pending application, Ser. No. D. 125,636, filed January 17, 1946.

I claim:

The ornamental design for a handle for hand luggage, as shown.

CLIFFORD BROOKS STEVENS.
